UNITED STATES PATENT OFFICE.

EDWARD P. HENRY, OF LONG BEACH, CALIFORNIA, ASSIGNOR OF ONE-HALF TO
GORDON H. CLARK, OF LONG BEACH, CALIFORNIA.

MOLD FOR CASTING CONCRETE STRUCTURES.

1,239,390.

Specification of Letters Patent.

Patented Sept. 4, 1917.

Application filed November 18, 1913. Serial No. 801,741.

To all whom it may concern:

Be it known that I, EDWARD P. HENRY, a citizen of the United States, residing at Long Beach, in the county of Los Angeles and State of California, have invented a new and useful Mold for Casting Concrete Structures, of which the following is a specification.

This invention involves the construction of poured walls, so termed in the art, and the mold or forms for their production.

An object of this invention is the production of concrete structures with minimum expenditure of time and money.

Another object is the production of a sectional mold of minimum weight and thickness and maximum strength and rigidity which can be assembled and knocked down with minimum labor and maximum expedition.

By the construction and arrangement of the elements of this invention, I propose with the labor of, say, four men to erect a mold for a small structure as, for instance, a bungalow and to pour the concrete for such structure in one day, and to manufacture larger structures in proportionately short periods of time.

More specifically stated I construct a substantially rigid mold frame of standards and latch bars, the latch bars connecting and locking the standards together, and said standards comprising pairs of outer and inner members or joists which are securely tied and keyed to one another to prevent relative movement of said joists. After the frame has been constructed or while it is still under construction, form plates are placed from standard to standard and are detachably fastened to the standards by latch bars overlapping adjoining edges of the plates so as to form tight joints to substantially prevent leakage of water and concrete while the concrete is yet in a fluid state.

It has heretofore been customary to draw the plans of a building structure without any special reference to the mold which is to be employed in molding the structure, that is, the structure is not confined to dimensions based on any particular unit of size. It is obvious that in this invention the form plates may be cut to such dimensions as will produce structures varying in size by a fraction of an inch, but this in-

vention contemplates that building structures be planned with a definite unit of dimension in view, so that such structures may be cheaply and quickly erected without waste of material; and for this purpose the mold is constructed of unit sections of a given dimension or multiples of such dimension.

Further objects and advantages may appear in the subjoined detail description and the drawings filed herewith and forming a part of this specification.

The accompanying drawings illustrate the invention.

Figure 1 is a plan view of my newly invented mold for casting a small bungalow or the like, with window and door frames in place.

Fig. 2 is an enlarged sectional detail of some of the parts in Fig. 1 on line indicated by α^2 , Fig. 3.

Fig. 3 is a sectional elevation on line indicated by α^3 , Fig. 2, a portion of one of the keepers being broken away for clearness of illustration.

Fig. 4 is an enlarged broken view on line indicated by α^4 , Fig. 5, with concrete in place.

Fig. 5 is a broken sectional elevation on line indicated by α^5 , Figs. 1 and 4, the concrete being omitted and portions of some of the inside plates being broken away for clearness of illustration.

Fig. 6 is an enlarged sectional detail on line indicated by α^6 , Fig. 5.

Fig. 7 is a sectional elevation on line indicated by α^7 , Fig. 6, omitting the standard member.

The elements hereinafter enumerated are preferably all of metal and may, of course, be constructed in different shapes than those specifically described and depicted in the drawings.

Standards 1 of the mold frame comprise pairs of opposing bodies or joists which have their exterior surfaces, relative to the completed mold, angular in cross-section, and the shapes of such joists vary according to the location of the standards. For instance, the joists may be composed of one or more members in the shape of angle irons 2 or T-irons 3 grouped as in the drawings, or may be constructed of any other suitable shapes grouped as deemed best for the structure to be built, and it is under-

stood that I at present prefer the shapes and groupings shown in the drawings but do not wish to limit the invention to such shapes and groupings.

5 As shown in Fig. 1 the standards 1 at the four corners of the mold may be formed by the angle irons 2 arranged in groups of two separate members; and the standards at the partition intersections may be formed 10 exteriorly by the T-irons 3 arranged singly and may be formed interiorly by the angle irons arranged in pairs, the T-irons and angle irons thus forming groups of three separate members; and other intermediate 15 standards may be formed entirely by the T-irons 3 arranged in groups of two separate members.

The joists 2, 3 are provided with perforations 4 to receive taper tie bars 5 which 20 are approximately square in cross section and provided with a series of oblong slots 6 disposed in the same direction and adapted to receive wedges 7, the spacing of said slots being an inch, more or less, in order 25 that the joists may be correctly spaced and locked for the formation of various thicknesses of walls, say from four to ten inches in thickness.

The wedges 7 are designed to engage 30 loops 8 provided on each joist to lock the joists of each pair against movement toward one another. The loops are arranged on the external faces of the joists or standards, that is to say, the faces that are externally 35 presented when the mold is completed, and a loop 8 is provided adjacent to and below each slot 6 and the wedge-keys 7 when driven through the slots 6 enter the wedge into said loops, thus rigidly tying the taper 40 tie bars and the joists or standards together.

Means are provided to complete the mold frame and to securely lock the standards 1 in place relative to and in parallelism with 45 one another, and for this purpose the joists 2, 3 are provided with keepers 9 made of twisted bars or the like and having notches 10 to receive and detachably hold the ends of 50 latch frame bars 11 having offsets 12, the purpose of which will appear hereinafter. The latch frame bars 11, in the instance shown, are formed of angle irons and to facilitate the formation of the offsets 12, the horizontal legs of the angle irons may 55 be cut away at their ends to produce notches 13 adjacent the offsets and notches, 10.

The latch bars 11 are provided near their 60 ends with slots 131 designed to engage the bottoms of the notches 10 so as to lock the joists of adjacent standards against movement toward and from one another. See Fig. 3.

Adjacent standards 1 are connected from 65 joist to joist with rectangular form plates of appropriate dimensions, and I prefer to

make the form plates in, say, two sizes 14, 15, the plate 14 being, for instance, eighteen inches by thirty-six inches, and the plate 15 being eighteen inches square, thus providing for the erection of the mold in units 70 formed, in this instance, in multiples of eighteen inches in length, width and height.

The form plates 14, 15 have offsets 16 near their ends to bring their inside faces substantially flush with the inside faces of the 75 joists 2, 3, said offsets closely fitting against the offsets 12 of the frame bars 11 and the upper and lower edges of said plates butting and being overlapped by the latch bars 11 which fit closely from end to end against 80 said plates and thus materially aid in making tight joints between adjacent plates.

The foregoing construction produces such great rigidity of the mold that ordinarily it 85 will not be necessary to employ any elements to stiffen the same other than those already enumerated, however, in case additional stiffening is desired, I provide braces or tie rods 17 designed to lie on the upper edges of the mold and adjustably connected 90 to opposite portions of the mold by forked clamps 18 and set screws 19 screw-threaded through the clamps and against the tie rods so as to fix the clamps at appropriate intervals along the brace rods in position to 95 straddle the upper ends of some of the joists 2, 3, as in Fig. 6, or any other convenient parts of the mold.

I propose to cast the walls of the structure with the door and window frames in 100 place and for this purpose perforations 20 are provided in the form plates at appropriate positions to accommodate detachable headed studs 21 on which the frames 22 are hung. See Fig. 5.

In practice the joists 2, 3 will preferably 105 be locked together by such means as the tie bars 5, wedges 7 and loops 8 to form the standards 1, either before reaching the site of the proposed building structure or after 110 transportation to such site before erection of the mold on the site selected or designed to receive the structure.

Then a standard 1, say at the corner of the proposed building or at any other preferred portion thereof, will be erected and plumbed and will be temporarily held in its plumbed position by guy lines indicated at 115 23 in Fig. 1.

Then a second standard will be erected 120 and rigidly fixed in parallelism to the first standard by connecting said standards at top and bottom with latch bars 11. This plumbs the second standard in accordance with the plumbing of the first standard.

Then other of the standards will be erected and connected one to the other by latch bars 11 in accordance with the building plans to complete a mold frame of the height of one tier of standards; and, in case 130

there are a number of workmen, while the erection of the standards goes on, the form plates 14, 15 will be placed edge to edge one above the other from standard to standard 5 and will be fastened to the standards by placing the latch bars 11 over the joints between adjacent plates and slipping the ends of said bars in notches 10 of the keepers 9; the frames 22 for the windows and doors 10 being hung in position on the studs 21 as the work proceeds.

If desired the brace rods 17 may then be secured in place to additionally stiffen the mold.

15 When one tier or more of the form plates, 14, 15 has been fastened in place, the operation of casting or pouring the walls may begin and as such operation is well understood it need not be described in detail, and 20 it is understood that the operation may be performed in any manner and by any means now known in the art or that may be known in the future.

25 Preferably the mold will be completed from bottom to top, at least at one section thereof before casting of the walls begins.

When the concrete has hardened sufficiently, as determined by practice and the judgment of the constructor, if the walls 30 are to be no higher than the one tier of standards, the latch bars 11 and form plates 14, 15 will be removed, then the wedges 7 will be removed from the slots 6 and then the tapered tie bars 5 will be hammered or 35 otherwise driven out of the wall α and standards 1, whereupon the standards will be removed from the structure.

40 If the walls are to be higher than the one tier of standards 1, the tapered tie bars 5 and wedges 7 will be allowed to remain in place to maintain the standards in their positions, and an upper second tier of standards will be erected in alinement with and on the upper ends of the lower tier of standards 45 and connected by latch bars 11, as before described, to produce the second tier of the mold frame.

Then as before described form plates will 50 be connected from standard to standard of the upper tier the same as for the lower tier and casting of the walls will proceed; and so on until the walls have been constructed to the determined heights, whereupon the standards of successive tiers from 55 top to bottom will be loosened from the walls by removing the wedges 7, thus allowing all of the standards and tapered tie bars 5 to be removed from the structure and the openings in the wall caused by the removal 60 of the tie bars may be filled with concrete if so desired.

The plates of the form tier immediately 65 below the plates of the next upper tier under construction are generally left in place until the operation of casting at said upper

tier is completed, whereupon said plates are raised by suitable tackle or the like, not shown, to the second tier of standards above.

To facilitate the use of such tackle, the plates 14, 15 are provided near their ends 70 with outwardly punched holes 24.

From the foregoing it will be seen that I not only propose to cast concrete to form continuous walled monolithic structures of a nature well known in the art; but that I 75 also propose to employ means which will expedite the manufacture of such structures; and that like a founder of metallic products, I first set up a rigid mold which on account of the size and variable dimensions of the 80 product, I make of interlocking sections, taking care that the rigidity of the mold is not materially impaired by making it in sections; and that to insure such rigidity I have conceived of the specific features here- 85 inbefore described.

I claim:—

1. A metallic mold for casting concrete structures, which mold comprises standards, each standard being composed of two separate members, there being oppositely disposed corresponding perforations in the members of each standard; taper tie bars for said standards, each of said tie bars being approximately square in cross section 95 and adapted to pass through said opposite perforations for connecting the members of each standard with each other, there being oblong slots disposed in the same direction and spaced apart throughout the length of 100 each tie bar; a loop below and adjacent to each of said perforations on such a surface of each member as is in an external relation to the completed mold; plates connected from member to member of adjacent standards; and wedges, each of which is adapted to engage one of said slots, one of said loops and one of said external surfaces for holding the respective members of each standard in a fixed relation to each other. 110

2. A metallic mold for casting concrete structures, which mold comprises, standards each composed of a single T-iron and two angle irons, means to lock said T-irons and angle irons against relative movement, 115 plates, and bars detachably fastening said plates to the T-irons and angle irons respectively of adjacent standards.

3. A metallic mold for casting concrete structures, which mold comprises; a frame 120 composed of corner standards, intermediate standards and bars detachably connected to the standards; said corner standards each consisting of two angle irons and said intermediate standards each consisting of two 125 T-irons; means to lock the angle irons and T-irons of the corner and intermediate standards respectively against relative movement; and plates fastened to the frame by said detachable bars. 130

4. A metallic mold for casting concrete structures, which mold comprises; a frame composed of corner standards, partition intersection standards, other intermediate standards and bars detachably connected to the standards; said corner standards each consisting of two angle irons, said partition intersection standards each consisting of a T-iron and two angle irons, and said intermediate standards each consisting of two T-irons; means to lock the angle irons and T-

irons of the standards respectively against relative movement; and plates fastened to the frame by said detachable bars.

In testimony whereof, I have hereunto set my hand at Los Angeles, California, this 1st day of November, 1913.

EDWARD P. HENRY.

In presence of—

JAMES R. TOWNSEND,
GEORGE H. HILES.
